CLAIM

The ornamental design for a molded barrel container, as shown and described.

DESCRIPTION

FIG. 1 is a perspective view of a first embodiment of a molded barrel container showing my new design; FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of the molded barrel container;

FIG. 9 is a front view of thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The circular elements in FIGS. 1, 2, 4, 5, 7, 8, 9, 11, 12, and 14 are surface ornamentation. The broken lines at the bottom edge of the article in both embodiments depict portions of the molded barrel container that form no part of the claimed design.

The broken lines represent portions of the molded barrel container and form no part of the claimed design.
